GIRDLE OR FOUNDATION GARMENT

Conrad Bullinger, Downers Grove, Ill., assignor
to A. Stein and Company, Chicago, Ill., a cor-
poration of Illinois

Application February 12, 1945, Serial No. 577,416

2 Claims. (Cl. 2-43)

This invention relates to improvements in women's under garments, such as typified by so-called girdles and foundation garments which are usually designed to supply support to the wearer's abdomen.

Conventional garments of this character are quite generally equipped with various arrangements of panels to supply the supporting function, such panels usually consisting of fabric which is inelastic and, in some instances, of fabric which is elastic only in one direction, usually in the horizontal direction. In girdle type garments, supporting panels of the said character have usually been equipped with some form of stay; that is to say, some form of flexible metal or bone supporting strip or strips arranged in pockets which usually terminate at the upper or waist-line edge of the garment. These stays have been required for the purpose of preventing folding of the upper marginal portion of the garment front downwardly, incident to the movement of the wearer, and especially incident to bending of the body as when a person sits down.

Many proposals have been made for strengthening the supporting panels so as to prevent them from becoming excessively wrinkled and for so arranging and perhaps for eliminating the supporting stays which are generally responsible for much of the discomfort complained against by wearers of these garments. The employment of stays which extend downwardly or at an angle from the upper edge of a girdle type of garment has long been known as being responsible for considerable discomfort experienced by wearers of the garments, especially when they are seated. When the body assumes a sitting position there is a strong tendency to fold the upper front marginal portion down on the garment but metal or other stays resist such folding and act like prongs which project into the wearer with consequent severe discomfort.

The main objects of the present invention are to provide garments of the character indicated with an abdominal supporting panel which will be highly effective to supply the desired support; to provide such garments with an effective supporting panel which is wholly free from rigid or semi-rigid stays or harsh reinforcing seams or other devices designed to supply the function of stays; to provide in garments of the character indicated, supporting panels which not only provide effective support but which may be so shaped or styled as to provide the garment with an attractive appearance which is of great importance in respect of the selling of the garments;

and to provide garment panel structures as aforesaid, which may be produced and embodied in garments at low cost both in respect of the material in the panel itself and in respect of the cutting of the panel to its required shape, and the joining of the panel to the other portions of the garment.

Other objects and advantages of the invention will be understood by reference to the following specification and accompanying drawing (one sheet) wherein the invention is illustrated as applied to a pantie girdle type of garment and to a foundation type of garment.

In the drawing:

Fig. 1 is a front perspective view of a pantie girdle type of garment;

Fig. 2 is a cross section on the line 2-2 of Fig. 1;

Fig. 3 is a front perspective of a foundation garment, and

Fig. 4 is a section on the line 4-4 of Fig. 3.

In the pantie girdle type garment shown in Fig. 1, the side, rear and leg portions constituting the main body 1 of the garment, may be formed of any suitable material such as a knitted or woven material which is elastic in the horizontal direction. The crotch part of the garment may be formed of a suitable knitted or woven inelastic insert 2 which may extend continuously from one leg into the other.

The central front portion of the garment is formed of a panel 3 which is, in this instance, of laminated construction. The panel 3 comprises an outer fabric member 4 of silk, rayon or other material which will provide the desired appearance, an inner ply or layer 5 of material such as cotton or shaker flannel which has a nap on the side which is inside of the garment and which contacts the body. The two layers or plies 4 and 5 are united in face to face relation over their entire areas by means of an intervening ply or coating 6 of rubber or rubber-like material, such as some of the now known vinyl resin compositions which have some of the properties of rubber and are, in effect, forms of synthetic rubber. The uniting coating 6 is preferably a moisture-proof, water insoluble coating which will not be dissolved or so affected by laundering in water or by perspiration that the bond between the outer and inner fabrics 4 and 5 would be materially impaired.

Fabric of the character described has the characteristic of a strong resistance to sharp folding and permanent creasing while at the same time remaining soft and flexible enough to be capable

of hugging the body of the wearer of the garment. The outer and inner fabrics 4 and 5 are preferably of non-stretchable material, especially in the horizontal direction of the garment, and preferably in all directions so that the panel will provide the required abdominal support.

Fabric such as employed in the panel 3 may be formed by applying a coating of the laminating material 6 on either the outer or inner fabric member and then applying the other fabric member, and passing the laminated fabric through suitable squeeze or pressing rolls to insure effective and all-over bonding between the plies of the fabric.

A sheet of laminated fabric of the character described may be cut to any fanciful shape without regard to the direction of the wales or threads of the fabric since the threads of the two fabrics are effectively anchored by the bonding ply 6 whereby there is no tendency for the fabric to unravel at its edge. Hence, the panel 3 with its fanciful downwardly pointed shaping and its concavely curved side edges may be cut from a piece of the fabric and united directly to the body 1 of the garment without taping, hemming or otherwise finishing the edges of the panel. This is illustrated in Fig. 2 where the raw cut edges of the panel are indicated at 7 and stitching uniting the panel to the body 1 of the garment is indicated at 8. This stitching may be of any suitable form and may of itself be such as to more or less ornament the garment, as indicated in Fig. 1.

For finishing the upper or waistline edge 9 of the garment, an elastic tape 10 may be secured to the inside of the garment and the upper edges of the body 1 and the upper edge of the panel 3 may be turned inwardly and downwardly so as to be covered by the band 10.

In the foundation garment shown in Figs. 3 and 4, an abdominal supporting panel 11 may be provided in the front portion of the garment 12. The panel 11 may be of the same kind of material as that described above in respect of the panel 3 and in this instance the panel 11 is illustrated as being located between inner and outer plies 13 and 14 respectively of net-like material forming a front panel 15 in the garment. The sides 16 of the garment may be of any desired material, for example, material which is stretchable both vertically and horizontally of the garment. A central back panel may be formed of net material, such as the material in the front panel 15.

The panel 11 is secured in place between the inner and outer plies 13 and 14 of the front panel 15 by stitching 16 which may follow the fanciful contour of the panel 11. The panel 11, like the panel 3, may be cut from a suitable sheet of the material and because of its laminated construction may be embodied in the garment without binding or otherwise treating its raw edges 17.

In Fig. 4, the panel 11 is illustrated as a single thickness of material which is in keeping with the manner of handling the material during the fabrication of the garment. It will, of course, be understood that the panel 11 consists of at least one ply of fabric and a ply of moisture-proof, water insoluble material having the characteristics of rubber in respect of its resistance to sharp folding and permanent creasing. Because of the presence in the arrangement shown in Figs. 3 and 4, of an inner ply of fabric independent of the panel 11, it is not essential that the panel 11 have its own inner fabric ply such as the fabric ply 5 of the panel 3.

Because of the inextensible or non-stretchable characteristic of the laminated fabric panels 3 and 11 in the garments described, these panels impart to the garment the desired abdominal supporting function. The normal resistance of rubber or rubber-like material embodied in the panels 3 and 11 to folding and permanent creasing does not interfere with bending of the garment as required when the wearer changes her position as from a standing position to a sitting position, but it has the advantage of causing the supporting panel to resume a flat, unwrinkled condition when the wearer resumes a standing position. It has been found that any wrinkled condition which may exist in the abdominal panel portion after a full day's wear of the garment will almost completely disappear during an overnight period in which the garment is not being worn. This is presumably due to the capacity of the rubber or rubber-like material to resume its normal or initial shape.

In a girdle type of garment, such as shown in Fig. 1, the described panel structure is particularly advantageous in that it eliminates the need for any form of semi-rigid stays. The panel 3 is free to fold downwardly, especially near its upper edge as is usually required when the wearer of a girdle changes from a standing position to a sitting position. There are no relatively stiff stays to resist such folding movement and to retain a more or less upright position to the severe discomfort of the wearer. Nevertheless the capacity of the material to return to its normal shape is such that when the wearer of the garment resumes a standing position the upper portion of the panel will also return to its normal, smooth, body-hugging condition without objectionable wrinkles or folds.

Another advantage of the described construction is that it avoids the usually necessary hems or other binding at the cut edges of the abdominal supporting panel, whereby the formation of thick, uncomfortable seam-like ridges is avoided along the panel edges where it is joined to the body of the garment.

The described constructions typify the application of the present invention and it will be understood that it is applicable to girdles and other garments which are not necessarily pantie girdles or foundation garments. Various changes may be made in the described construction while retaining the principles of the invention.

I claim:

1. A garment of the class described having a horizontally stretchable body portion and an abdominal supporting panel, said panel being of laminated construction embodying an inextensible textile fabric ply and a ply of flexible, water insoluble material united over its entire area in face-to-face relationship to said textile ply, said water insoluble ply being of material which has a live rubber-like resistance to permanent folding and creasing and thereby tends to restore the panel from any folded or wrinkled condition to a normally smooth condition, said panel serving, when the garment is distended and stretched horizontally while being worn, to permit the abdominal covering area of the garment to freely bend and wrinkle when the wearer bends as when changing from a standing to a sitting position, and to restore said abdominal covering area of the garment to smooth, body hugging condition when the wearer resumes a standing or straightened position, said panel serving also,

when the garment is not being worn, to effect self ironing of said abdominal covering portion of the garment.

2. A garment of the class described having a horizontally stretchable body portion and an abdominal supporting panel, said panel being of laminated construction embodying a pair of inextensible textile fabric plies and an intervening ply of water insoluble material uniting said fabric plies in face-to-face relationship over substantially their entire areas, said intervening ply being of material which has a live rubber-like resistance to permanent folding, wrinkling and creasing and thereby tends to restore the panel

5 from any folded or wrinkled condition to a normally smooth condition, said panel serving when the garment is distended and stretched horizontally while being worn to permit the abdominal covering area of the garment to freely bend and wrinkle when the wearer bends as when changing from a standing to a sitting position, and to restore said abdominal covering area of the garment to smooth, body hugging condition when 10 the wearer resumes a standing or straightened position, said panel serving also, when the garment is not being worn, to effect self ironing of said abdominal covering portion of the garment.

CONRAD BULLINGER.
